UNITED STATES PATENT OFFICE.

JOSEPH J. WHITE, OF PROVIDENCE, RHODE ISLAND, ASSIGNOR TO J. J. WHITE MANUFACTURING COMPANY.

SAFETY-CATCH FOR BREASTPINS AND THE LIKE.

1,359,008.

Specification of Letters Patent.

Patented Nov. 16, 1920.

Application filed March 1, 1920. Serial No. 362,512.

To all whom it may concern:

Be it known that I, JOSEPH J. WHITE, a citizen of the United States, residing at Providence, in the county of Providence and State of Rhode Island, have invented certain new and useful Improvements in Safety-Catches for Breastpins and the like, of which the following is a specification.

The invention has for an object to effect improvements in keepers and fasteners for the pin elements of brooches and the like, and has for an object to effect betterments therein of a character to improve the functions of such devices and to attain new results therein. It is an aim to provide a keeper device which will automatically close over a pin as the pin is pressed into a stationary furcated element, especially of a character to apply greater force to the starting movement of the keeper element by engagement of the pin whereby means may be provided to hold the keeper yieldably in open position without liability of interfering with the closing operation of the device or making it difficult; and the means by which this increase of force attained also operates to afford greater movement to the keeper than is possible in prior devices having pin operated keepers arranged to close over a pin by movement of the pin to closed position. Another purpose of the invention is to construct the keeper element and stationary member in such fashion that they will cooperate with the pin member to prevent accidental opening of the keeper device.

Additional objects, advantages and features of invention reside in the device and will be apparent from the following disclosure, including drawings, in which,

40 Figure 1 is a side elevation of a brooch and pin-keeper constructed in accordance with my invention, approximately actual size.

Fig. 2 is an outer side elevation of the keeper device proper, greatly enlarged,

45 Fig. 3 is a similar view showing the device in closed position,

Fig. 4 is a front elevation of the keeper,

Fig. 5 is a rear elevation thereof,

50 Fig. 6 is an inner side elevation,

Fig. 7 is a top view thereof, with the parts in open position.

There is illustrated a base bar 10 of a brooch upon which any usual or special ornamental work may be mounted, this bar

having ears 11 thereon at one end between which there is pivoted a usual form of spring 12 provided with a heel 13 by which the point of the pin is caused to spring outwardly, or away from the bar 10. A keeper 60 14 is provided upon the bar adjacent the end opposite the one having the ears 11 thereon, this keeper device comprising a base body adapted to be stamped from sheet metal and bent into a U-shaped shape, to provide 65 spaced ears 15 and 16, with a connecting bight portion 17 at the base, which may be soldered or otherwise secured upon the bar 10; and pivoted between the ears 15 and 16 there is a keeper proper 18. 70

The ear 15 is sloped toward the rear side 19 of the bar 10, and the ear 16 has a rear portion extending an equal distance toward the rear. Between the outer part of the ear 15 and the rear part of the ear 16, there is 75 fixed a pivot pin 20, carrying the keeper 18. Two jaws 21 and 22 respectively are formed on the ear 16, the one being projected upwardly above the pin 20, which is located rearwardly of the medial longitudinal vertical plane of the device. The forward side of the jaw 21 is inclined forwardly toward its lower part, forming one side of an inclined slot 23 between the jaws. The front jaw 22 therefore has a rearward inclination 80 85 toward its upper part to form the front side of the slot. The slot terminates at its lower part on a plane adjacent the axis of the pin 20 and is of a suitable width between the jaws to freely receive the pin 12 for oscillation therein.

The keeper 18 comprises primarily a hook portion 24, the base of which receives the pin 20 therethrough, and projected forwardly from the base of the keeper there is 95 an operating jaw and detent member 25 serving three functions as will be subsequently explained. The jaw 25 is broadened so as to form a stop portion 26 adapted to strike the bottom of the bight between 100 the ears 15 and 16 when the keeper is in closed position, as shown in Fig. 3. At this time, the upper side of the jaw extends approximately horizontally closely adjacent or on a level with the bottom of the slot 23. 105 The bill 27 of the hook 24 is so formed that when the device is in closed position the inner face of the bill extends vertically a short distance, or in such relation to the opposing face of the stationary jaw 21 that 110

upon opening movement of the keeper device when the pin is engaged therein, the pin will be caught between the jaw 21 and the hook bill, and opening movement of the keeper prevented, unless the pin is depressed so that the hook may clear it. The opposed faces of the hook and jaw 21 in the present construction are nearly or quite parallel when the pin becomes coengaged therebetween, although a slight variation from parallelism is permissible, owing to the outward pressure of the pin. The point portion of the jaw 25 is bent laterally to a slight extent, as clearly shown in Fig. 7, so that it engages between the jaws 21 and 22 when the keeper device is in open position, and being snugly held between the ears 15 and 16, a slight wiping action occurs between the point portion of the operating jaw and the stationary jaw 22, an inclined portion being presented to the jaw 22 so that initial movement of the keeper from open position is slightly retarded, the device being yieldably detained in open position in this way.

25 The keeper is provided with a finger piece 29, located upon the outer edge of the bight of the hook 24, where it may be conveniently reached for opening of the device when necessary. The keeper is also provided with 30 a heel lug 30 upon its rear edge, so arranged as to strike against the rear part of the bar 19 when the device is moved to full open position.

It will be seen that when the device is 35 in open position the pin member 12 becomes wedged between the outer parts of the operating jaw and the stationary jaw 21, so that a slight pressure upon the pin is sufficient to overcome the resistance of the point 28 to opening movement of the keeper. Continued pressure upon the pin 12 causes it to pass downwardly through the slot 23 moving the jaw 25 until the stop portion 26 engages against the base of the device as 40 shown in Fig. 3. The hook will then have been moved across the slot 23 so that its inner surface is alined with the upper end portion of the jaw 22, which is suitably formed for the purpose. Release of the pin 45 12 will then permit it to spring outwardly into the hook of the keeper. Opening of the device is accomplished by pressing upon the pin 12 until it moves into the lower part of the slot 23, and then pressing upon 50 the fingerpiece 29 to move the keeper into open position. The point 28 of the keeper bears upon the arm 22 throughout the movement of the keeper, so that loose movement of the parts is prevented at all times.

60 What is claimed is:

1. A pin keeper for brooches and the like comprising a body element having stationary jaws thereon shaped to form a pin receiving slot therebetween, a keeper element pivoted laterally of the lower part of the

slot, and having a hook portion movable into closed position over the outer part of the slot to aline therewith, said keeper including an operating jaw member having a face positioned to lie across the lower part 70 of the slot when the device is in closed position, and to set at an angle and in close relation at its outer part to one of said first named jaws to receive a pin member in wedging engagement between their outer 75 parts for sliding movement into the slot and on said operating jaw, and a pin member mounted and constructed to be held resistingly in said device, and of a size to wedge as described.

2. A pin keeper for brooches and the like comprising a body element having stationary jaws thereon shaped to form a pin receiving slot therebetween, a keeper element pivoted laterally of the lower part of the 80 slot, and having a hook portion movable into closed position over the outer part of the slot and alined therewith, said keeper including an operating jaw member having a face positioned to lie across the lower 85 part of the slot when the device is in closed position, and to set at an angle to one of said first named jaws to receive a pin member in wedging engagement between their outer parts for sliding movement into the slot and on said operating jaw, a pin member mounted and constructed to be held resistingly in said device, said hook member being positioned at an angle to one of said stationary jaws to engage the pin 90 member so as to prevent opening movement of the keeper; said operating jaw having a laterally turned portion to engage yieldably between said stationary jaws.

3. A pin keeper for brooches and the like 105 comprising a body element having stationary jaws thereon shaped to form a pin receiving slot therebetween, a keeper element pivoted laterally of the lower part of the slot, and having a hook portion movable 110 into closed position over the outer part of the slot and alined therewith, said keeper including an operating jaw member having a face positioned to lie across the lower part of the slot when the device is in closed 115 position, and to set at an angle to one of said first named jaws to receive a pin member in wedging engagement between their outer parts for sliding movement into the slot on said operating jaw, a pin member mounted and constructed to be held resistingly in said device, said hook member being positioned at an angle to one of said stationary jaws to engage the pin member 120 so as to prevent opening movement of the keeper, said operating jaw having an extension to engage against the base of the device to check movement of the keeper toward closed position.

4. A pin keeper for brooches and the like 130

comprising a body element having stationary jaws thereon shaped to form a pin receiving slot therebetween, a keeper element pivoted laterally of the lower part of the 5 slot, and having a hook portion movable into closed position over the outer part of the slot and alined therewith, said keeper including an operating jaw member having a face positioned to lie across the lower 10 part of the slot when the device is in closed position, and to set at an angle to one of said first named jaws to receive a pin member in wedging engagement between their outer parts for sliding movement into the 15 slot on said operating jaw, a pin member

mounted and constructed to be held resistingly in said device, said hook member being positioned in a relation to one of said stationary jaws to engage the pin member so as to prevent opening movement of the 20 keeper, said keeper device having a heel extension thereon to engage the base of the device under opening movement to check the keeper in receiving position as described.

In testimony whereof I have affixed my 25
signature in presence of two witnesses.

JOSEPH J. WHITE.
